UNITED STATES PATENT OFFICE.

JOHN SUMMERFIELD, OF DALLAS, TEXAS.

ACETYLENE-GAS GENERATOR.

SPECIFICATION forming part of Letters Patent No. 737,524, dated August 25, 1903.

Application filed November 26, 1902. Serial No. 132,853. (No model.)

To all whom it may concern:

Be it known that I, JOHN SUMMERFIELD, of the city of Dallas, in the county of Dallas and State of Texas, have invented certain new and useful Improvements in Gas-Generators, of which the following is a specification.

This invention relates to improvements in gas-generators, and particularly to gas-generators for generating gas from carbide; and the object is to provide generators which are economical and practical and perfectly automatic in action and which will be free from danger of explosions.

Other objects and advantages will be fully explained in the following description, and the invention will be more particularly pointed out in the claims.

Reference is had to the accompanying drawings, which form a part of this application and specification.

Figure 1 is a side elevation of the entire apparatus, a part of the storage-tank being broken and shown in section. Fig. 2 is a vertical section of one of the generating-chambers. Fig. 3 is a plan view of one of the generating-chambers. Fig. 4 is a detail enlarged plan view of one of the sprinklers. Fig. 5 is a side elevation of the same, showing the manner of mounting the sprinkler. Fig. 6 is a side elevation of the switching mechanism, a part of the locking-bar being broken away to show the parts which would have been hidden from view by the locking-bar. Fig. 7 is a perspective view of the locking-bar and the tripping-bar. Fig. 8 is a side elevation of one of the switching-keys on a larger scale than Fig. 6. Fig. 9 is a vertical section of the drier.

Similar characters of reference are used to indicate the same parts throughout the several views.

This invention is provided with a storage-tank 1 for gas, and this tank is provided with means for sealing the gas in the tank with a suitable liquid. A liquid-tank 2 is attached to the tank 1 in the same manner as the liquid-tank 3 is attached to the generating-chamber 4 in Fig. 2. Liquid is placed in the tank 2; but care must be exercised, so that there will never be enough liquid to rise as high as the top of tank 1. A gas-bell 5 is mounted in the tank 2. The gas-bell 5 may be pressed downward by any suitable weight 6, placed on top

of the bell 5. Two generating-chambers 4 and 7 are provided, and means are provided for using each generating-chamber alternately and storing the gas from each chamber in the storage-tank 1. The object is to arrange the generating-chambers so that gas will be generated in one until the carbide is exhausted and then automatically to switch the water-feeding mechanism, so that gas will be generated in the next chamber. A water-tank 8 is provided for feeding water to either generating-chamber. Tank 8 is provided with a pipe 9, and the pipe 9 is provided with a cut-off valve 10 and a union 11. Pipe 9 is further provided with an automatic valve 12, or a valve 12 which is automatically operated by means of a segment or spur 13. This spur 13 has a notch 14 in one side, and the spur is mounted on the valve-stem or shaft 15, which rocks the valve to open or close the same. The pipe 9 is connected by means of suitable elbows to the pipe 16. The pipe 16 is connected by means of a pipe 17 to a pipe 18, whereby the pipe 9 will deliver water to either pipe 16 or 18. A plug 19 is inserted in the pipe 18 opposite the entrance of pipe 17, so that pipe 17 may be cleaned without taking the pipes down. The automatic cut-off valve 12 is mounted in pipe 9, so that the flow of water to either pipe 16 or 18 may be regulated by one cut-off or a common cut-off valve. By such arrangement only one tripping mechanism is necessary.

The manner of operating the cut-off valve 12 will next be described. A tripping-bar 20 is mounted on the gas-bell 5 by means of a bar 27, which is attached to the gas-bell. The upper part of the bar 20 is threaded and made adjustable as to height by means of nuts 21 and 22. The lower part of the tripping-bar 20 is bent to form a tripper 23, which engages the spur 13 in the notch 14 for turning the said spur. When the machine is not in use, the tripping mechanism stands in the position shown in Fig. 1. When water is turned on by means of cock 10 in the water-pipe, water will reach the carbide in one of the generators and gas will be generated until the pressure becomes strong enough to raise the gas-bell 5, and thus carry the tripper 23 upward. In moving upward the tripper will engage the spur 13 in notch 14 and turn the spur, and

thus cut off the water-supply. A locking-bar 24 is bolted to the bent part of the bar 20 (this bar 20 being wide enough to form the tripper 23 and to leave an extended portion 5 25 for attaching the bar 24) for locking the valve 12 open by means of pins 26, which are inserted in the spur 13. Immediately after the tripper turns the spur 13 the bar 24 passes up and comes flush with the pins 26 in the 10 position shown in Fig. 6. The bar 24 thus locks the valve 12 closed until the tripper 23 comes down and turns the spur back to the position shown in Fig. 1. The gas-bell 5 descends as the gas is consumed, and the gas-bell 15 carries the tripper 23 down, so that this tripper will engage the spur to open the valve to turn water on the carbid again, whence more gas will be generated and the tripper will go up and cut off the water as before. 20 This operation will continue until all the carbid in one chamber is spent. It will be understood that the machine will stand still with a supply of gas in the gas-bell when no gas is being used. The bar 27 is guided in 25 its upward and downward motion by two rods 28, which have heads 29 to prevent the bar 27 from going off and which are threaded and screwed into jam-nuts and lock-nuts 30, attached to the tank 2. The bar 20 is held in 30 the proper vertical position by the bar 27.

The generating-chambers are alike in construction and the description of one will be sufficient. Each generator is provided with a water seal. Each chamber is provided with 35 and mounted on a pipe 31. The pipes 31 are provided with water and gas tight valves 32 and are mounted on blocks 33, which have recesses 34 cut therein, which recesses form gutters extending under the pipes 31 to carry 40 away spent carbid or ashes and water. A grate or rack 35 is mounted in each chamber to support the carbid. A water-tank 3 surrounds the upper part of each chamber, and is attached thereto in the position shown in 45 Fig. 2. A gas-bell 36 is mounted in each water-tank 3 and surrounds the upper part of each generating-chamber and the water and gas-pipes leading to and from the mouth of each chamber. Each gas-bell 36 is locked 50 down in each water-tank 3 by means of a bar 37, which is attached to the top of the gas-bell and has a part 38 bent up near the middle part to form a handle. The ends of the bars 37 are engaged by hooks 39, which may 55 be soldered to the sides of the water-tanks. The points of the hooks on the tank extend in opposite directions, so that the bar 37 will be engaged by the hooks when the gas-bell is placed in the water-tank with the bar 37 resting 60 on top of the water-tank and the gas-bell is slightly shifted.

Means are provided for delivering water to each generating-chamber alternately. The manner of directing water to the pipes 16 and 18 is described above. Valves 40 and 41 are mounted, respectively, in pipes 16 and 18, and these valves are set with their openings so

that when one valve is open the other is closed. Flexible pipes 42 and 43 connect the pipes 16 and 18, respectively, with 44 and 45, which 70 carry the water to the sprinklers 46. Means are provided for switching the water from one generator to the other alternately. The valves 40 and 41 are provided with rock-shafts 47 and 48, and keys 49 and 50 are mounted on 75 the shafts or valve-stems 47 and 48 for opening and closing the valves 40 and 41. The keys 49 and 50 are made to operate simultaneously, but they have a very slight movement relative to each other. This movement 80 relative to each other in the keys 49 and 50 is necessary because of the difficulty of grinding the valves exactly true. The keys would move independent of each other if they were not locked together by pins 51 and 52, which 85 are mounted on the keys 49 and 50, respectively. The pin 51 is attached to the key 49 and will cause the keys to move together in turning in one direction, and the pin 52 is attached to the key 50 and will cause the keys 90 to move together in the other direction. One pin being attached to one key and the other pin being attached to the other key will allow sufficient movement of the keys relative to each other. Unless there is some movement 95 of the keys relative to each other the key on one valve-stem or rock-shaft might not open or close properly the valve which is operated by the other key. The keys are operated by a tripping-lug 53, which is bolted to bars 20 100 and 24, and by the weighted arms 54, 55, 56, and 57, which are pivotally mounted on the key 49 by means of pins 58, inserted at one end in the key 49. Stop-pins 59 are also mounted in the key 49 to limit the outward movement 105 of the pivoted arms. Weights 60 are attached to the outer ends of the pivoted arms to make these arms fall promptly from the position shown by arm 54 in Fig. 8. In this position the tripper 53 is supposed to be against arm 110 55 and just about to pass below the arm. As soon as the tripper 53 releases the arm 55 the arm 54, which is resting on the arm 55, will drop and rest on the pivot 58 and project in the path of the tripper or lug 53. When the lug 115 53 passes up, it will strike the arm 54 and push it out of the path and go on up above this arm, because this arm has sufficient movement to allow the lug 53 to pass up without turning the valve or key 49. As soon as the lug 53 passes 120 above the arm 54 this arm will drop back against the pivot 58. When the lug 53 again descends, it will engage the arm 54 and press the same down and in doing this will turn the keys 49 and 50 sufficient to open one valve 125 and close the other in pipes 16 and 18. Arm 57 will then occupy the position previously occupied by the arm 54, and arm 56 will take the position of the arm 57, &c. It will be seen that the keys 49 and 50 will be rotated in one 130 direction and that each time the lug 53 passes down the keys will be rotated one-quarter or ninety degrees. Every time this is done one valve will be opened and the other closed in

pipes 16 and 18. For instance, if the valve 40 is open and the valve 41 is closed the lug 53 on passing down will engage one of the arms pivoted on the key 49 and rotate the keys ninety degrees and close valve 40 and open valve 41. The lug 53 in passing up does not rotate the keys, because the arms on the key 49 will swing far enough out of the way of the lug without rotating or moving the keys. Whenever valve 40 is closed and valve 41 is opened, water is switched from generator 4 to generator 7 and vice versa when valve 41 is closed and valve 40 opened. Water is delivered through pipes 44 and 45 to sprinklers 46, which drops the water on the carbid placed on the grates 35. The sprinklers consist of cone-shaped and corrugated sheet-metal pieces which are supported by wire stems 61 in the pipes 44 and 45. Each sprinkler has partitions or upwardly-extending flanges 62, which extend up to and the edges thereof are flush with the wire stem 61. The object of these flanges is to divide the water and start the same to all parts of the sprinkler. The flanges 62 are mounted on the upward bends of the corrugations of the metal.

The gas is carried from the generating-chambers 4 and 7 by means of pipes 63 and 64, which are united by a T-section 65 to a common pipe 66, which connects with the storage-tank 1. Each pipe 63 and 64 is provided with a cut-off valve 67, which is also a safety-valve. The cut-off valves are provided so that each generator may be cut off from the storage-tank at will for the purpose of replenishing with carbid. The valves 67 are made safety-valves, so that if a party were to fail to open the valve after water was turned on the carbid gas would escape without causing an explosion. An explosion is not probable, because the gas-bells 36 rest in water or other liquid. The gas would pass under the lower edge of the gas-bell 36 and then escape between the gas-bell and the water-tank 3. This is one of the advantages of the water seal. Another advantage of the water seal is that the water makes a perfect seal. The safety-valves being an ordinary three-way valve, will also let in air when the generator is cut off from the storage-tank. The advantage of this is that the gas-bell can be taken off. If no air were allowed to pass into the generator, the atmospheric pressure would make the removal of the gas-bell difficult. The gas-pipes 63 and 64 extend near the top of the generating-chambers, and the upper parts of the gas-pipes are protected by housings 68. Recesses are cut in the top edges of the generating-chambers to allow the gas to pass into the gas-pipes. The water-tanks 3 are provided with drainage-cocks 69. The water-tank 2 is provided with a drainage-cock 70, and the storage-tank 1 is provided with a drainage-cock 71. As the gas is taken from the storage-tank 1 for use it is passed through a drier. A pipe 72 delivers the gas to the drier. The drier consists of a large T-pipe section 73.

Each opening is plugged with a suitable bushing 74. The pipe 72 runs through the bushing 74 to the interior of the drier, and the mouth of the pipe is covered with a bag 75 of suitable cloth or porous material of some kind to arrest any particles of foreign matter which may be passing up with the gas. The drier is provided with a drainage-cock 76, which runs through the bushing 74. A service-pipe 77 leads out of the drier.

In use one or both of the generators may be used. The object in providing two generators is that there will always be gas for making lights and so that the lights will not go out when the carbid is used up in one generator. Water is placed in the water-tank and water or oil is placed in the tanks surrounding the gas-bells for sealing purposes. Carbid is placed in the generators. To start the machine, open the cock or valve 10. Set the key 49 so that the valve 40 will stand open. Water will be sprinkled on the carbid in generator 4. Gas will be generated and pass to the storage-tank 1. The gas-bell 5 will rise as the gas accumulates and carry the lug 53 upward without turning the keys 49 and without disturbing the valve 40. As the bell 5 continues to rise the spur or tripper 23 will engage the spur 13 in notch 14 and turn this spur, and thus close the valve 12 and cut off the water-feed. As the bell 5 continues to rise the bar 24 will lock the valve 12 closed until the gas is consumed out of bell 5 enough to let this bell descend. On descending the tripper 23 will again engage the spur 13 and open the valve 12. Water will again feed to generator 4 and gas will be generated and the bell 5 will rise again before it goes low enough to cause the lug 53 to disturb the keys 49. This operation will continue until all the carbid is spent in the generator 4. When the gas is consumed and the bell 5 descends, the lug 53 will turn the keys 49 and close the valve 40 and open the valve 41. This will switch the feed-water to the generator 7. The operation will then continue as above described for generator 4. While the generator 7 is in operation generator 4 may be recharged with carbid by simply cutting communication off from storage-tank by turning the valve 67 in pipe 63. After the generator is recharged the valve 67 may be opened, and then generator 4 is ready for use. When the carbid is spent in chamber 7, the lug 53 will switch the feed-water to chamber 4, as above described. Either generator can be charged while the other is in use.

Many changes may be made in the construction and arrangement of the various parts without departing from my invention.

Having fully described my invention, what I claim as new, and desire to secure by Letters Patent, is—

1. A gas-generator having one or more generating-chambers, a gas-storage tank, suitable pipes connecting said parts, and means for sprinkling water on carbid used for gen-

erating the gas consisting of a suitable pipe for conveying water to the generating-chamber, a sprinkler mounted in the generating-chamber and hanging loosely in the end of 5 said pipe, and means for controlling the flow of water through said pipe, said sprinkler consisting of a cone-shaped corrugated piece of sheet metal having upwardly-extending flanges adapted to direct the water in the 10 creases of said sprinkler.

2. A gas-generator having a generating-chamber, a water seal for said chamber, a gas-storage tank, a suitable pipe connecting said parts, and means for distributing water 15 on carbid in said generating-chamber consisting of a pipe for conveying water into said chamber, a corrugated cone-shaped sprinkler provided with a stem whereby said sprinkler is loosely mounted in the end of said water- 20 pipe, and upwardly-extending flanges having their upper ends flush with said stem and adapted to direct water to the creases of said sprinkler.

3. A gas-generator having a water-supply 25 tank, a water-sealed generating-chamber, a pipe connecting said chamber and said tank, a gas-storage tank connected to said chamber, and means for automatically turning on and cutting off the water-supply consisting 30 of a valve mounted in the water-supply pipe, a spur or segment attached to said valve and having a notch in one side thereof, a bar carried by said storage-tank, and a tripping-bar carried by said bar and provided with a spur 35 adapted to engage the notch in said segment as said storage-tank rises and descends.

4. A gas-generator having a gas-storage tank, two generating-chambers, suitable pipes connecting said chambers with said storage- 40 tank, each generating-chamber consisting of a central vessel having a rack for supporting carbid therein, a water-tank circumscribing the upper part of said vessel, a gas-bell resting in said water-tank and circumscribing

the upper part of said vessel, and means for 45 locking said gas-bell to said water-tank, and means for automatically sprinkling water on the carbid in each generating-chamber alternately.

5. A gas-generator having a storage-tank, 50 two generating-chambers, suitable pipes connecting said chambers with said storage-tank, each generating-chamber having a rack for supporting carbid therein, means for sealing the chamber with a liquid, and means in the 55 lower part thereof for removing the spent carbid, and means for sprinkling water in each generating-chamber.

6. A gas-generator having a storage-tank for gas, two generating-chambers, suitable 60 pipes connecting said generating-chambers with said storage-tank, means for supplying said generating-chambers with water, means actuated by said storage-tank for automatically cutting off and turning off the water-supply, and means for automatically switching the water-supply from one generating-chamber (when the carbid is exhausted in that 65 chamber) to the other consisting of valves mounted in the pipes conveying the water-supply, keys attached to the valve-stems, one of said keys being adapted to move the other key, a tripping-lug carried upward and downward by said storage-tank, and swinging arms mounted on one of said keys and adapted 70 to project in the path of said tripping-lug successively whereby said key is turned one-quarter over when said lug passes down, said valves being set so that one is open while the other is closed.

In testimony whereof I set my hand, in the presence of two witnesses, this 18th day of October, 1902.

JOHN SUMMERFIELD.
